CLAIM

The ornamental design for a combined set of table mats and stand, as shown and described.

DESCRIPTION

FIG. 1 is a front, top perspective view of the set of table mats and stand showing my new design;

FIG. 2 is a front, bottom perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof;

FIG. 8 is a bottom plan view thereof;

FIG. 9 is a front, exploded perspective view thereof, showing the table mats and the stand separately;

FIG. 10 is another front, exploded perspective view thereof, showing the table mats and the stand separately wherein the table mats are unfolded; and,

FIG. 11 is a top plan view of a table mat shown removed for ease of illustration; and

FIG. 12 is a bottom plan view of a table mat.

The broken lines shown in the figures depict portions of the article that form no part of the claimed design.
